SPRAYER FOR PRINTED SHEETS

George E. Hieber, Cincinnati, Ohio, assignor, by
mesne assignments, to The Sprayomatic Prod-
ucts Company, Cincinnati, Ohio, a corporation
of Ohio

Application December 7, 1934, Serial No. 756,497

1 Claim. (Cl. 91—16)

The present invention relates to a device for spraying newly printed sheets, to obviate adhesion between adjacent sheets and also prevent offset from subjacent sheets during the initial 5 stacking or subsequent operation.

An object of the invention is to provide a spraying device, capable of being controlled by any movable member on a printing press which is synchronized with the sheet moving mechanism.

Another object of the invention is to provide an automatic sprayer which will operate satisfactorily when a relatively quickly solidifying substance is used as the spraying fluid.

A further object of the invention is to provide 15 a spraying means of low initial cost and economical operation and adaptable to all types of printing presses.

Referring to the drawing:

Fig. 1 is a detail view of the delivery end of a 20 printing press showing my invention adjacent thereto.

Fig. 2 is a side elevational view of my invention.

Fig. 3 is a sectional view taken on line 3—3 of 25 Fig. 2.

My invention is most desirable in the art at the present time. This is due in part to the elaborate apparatus, deemed necessary, to accomplish an otherwise simple process, to the large 30 initial cost of conventional devices and to a general belief that spraying fluids should necessarily be liquid under heat and solid at lower temperatures to secure the best spraying results. My invention seeks to remedy these deficiencies by 35 introducing a device which is of comparatively simple construction and of low initial cost with the added features of adaptability and adjustability to all types of presses. My device may also employ a great variety of suitable spraying fluids 40 without impairing its operating efficiency.

The embodiment of my invention consists of an enclosed electric switch 6 suitably mounted on the delivery end of a printing press 7 in such position as to be actuated by a lever arm 8 comprising a part of the sheet moving mechanism. For the purpose of illustration the sheet moving mechanism consists of a driven cam 9 which imparts longitudinal reciprocating movement to a sheet moving shaft 10 by means of suitably pivoted drive shafts 11 and 12.

The switch 6 is enclosed in a box 13 which contains an opening to receive an electric commercial socket 14 and also a slot 15 to allow longitudinal movement of an arm 16. The arm is pivoted on a shaft 17 positioned on one vertical wall

of the switch box. A mercury tube 18 suitably mounted on the arm is employed to close contacts 19 and 20 of the two circuit leads 21 and 22 when the arm is in a relatively vertical position. After each actuation a spring 23 engaging the arm returns the switch mechanism to an open position. An insulated current-carrying line 24 associates the switch with a solenoid 25. The current is introduced through a plug 26 connected in series to the line 24. A plug 27 and socket 28 supported upon the solenoid by braces 29 and 30 conducts the current to the solenoid through leads 31 and 32.

The solenoid 25 and spray gun 33 rest upon a base 34. A rectangular box-like casing 35, pivotally mounted upon the base by hinge 36, permits easy accessibility to the operating parts. The casing contains an opening 37 in its top face to allow for the electrical plug and socket communication. Another opening 38 in the front face of the casing is of sufficient size as to permit a clearance of the protruding spray nozzle 61 when the casing is swung open about hinge 36. A lock 40 positioned on the base securely clamps the casing in a closed position.

A stand 41 and a telescoping pipe member 42 supports the spraying mechanism at any desired height.

The spray gun may be any suitable type in general use. It is mounted upon the base by two angle bars 43 and 44. The angle bars 45 and 46 comprising the support for the swivel joint 41 are fastened upon the bottom of the base.

Air under pressure enters the air valve chamber of the spray gun by hose connection 48 which also communicates with a compressed air machine (not shown) by hose 49. A T elbow carries air from the air line to the surface of the spraying fluid contained in the reservoir 50 thus forcing the fluid through hose 51 to the fluid valve 40 needle 52 in the spray gun. A trigger 53 pivotally mounted in the spray gun simultaneously controls the air needle 54 and the fluid needle 52 within the gun. The trigger is associated with the solenoid plunger 55 by means of a pivotally mounted link 56 which acts through a recess 54 in the gun handle. The link is tapered into a slotted bolt 57 to receive the trigger, and nuts 58 are employed to adjust the trigger and plunger action.

From the above description it will be seen that the switch may be actuated by any movable member on the press which is synchronized with the sheet moving mechanism. The gun itself may be adjusted to direct a spray in any desired di- 55

rection and as shown in Fig. 1 is adjacent the stacking mechanism 59 adjusted to direct spray upon newly printed sheets as they are stacked.

Any suitable fluid which possesses a quickly solidifying quality such as a mixture of alcohol, water, dextrose and salicylic acid may be used in conjunction with my apparatus.

What I claim is:

In combination with a printing press having a discharge end, means for receiving and stacking individual sheets of work printed by the press and means movable back and forth for transferring printed sheets from the discharge end of the press to the receiving and stacking means, of an electrical circuit controlling means disposed in the path of movement of said back and forth moving means of the press, whereby said circuit controlling means is actuated in timed relation with the discharge of printed sheets from the press for alternately opening and closing an electrical cir-

cuit, a base independent from and disconnected from said press and positioned adjacent to the discharge end of the press, an electrically operable spray device disposed upon the base to discharge a spray of quickly drying fluid substance over sheets as the sheets are moved from the discharge end of the press to the receiving and stacking means, and a source of electrical energy in electrical connection with said circuit controlling means and said electrically operable spray device, whereby upon opening and closing of a circuit including said source of electrical energy, said circuit controlling device and said electrically operated spray device, the spray device is rendered operative and inoperative in alternate sequence for spraying printed sheets during the period of transfer only of said sheets to said sheet receiving and stacking means.

GEORGE E. HIEBER. 20
